FLEXIBLE HEADWEAR

Seth Adamson, Larchmont, N. Y., assignor to
United States Rubber Products, Inc., New York,
N. Y., a corporation of Delaware

Application March 22, 1935, Serial No. 12,375

2 Claims. (Cl. 2—195)

This invention relates to an article of flexible headwear, more particularly to headwear of the brimless type, such as a cap or beret.

Numerous attempts have been made to produce 5 adjustable flexible articles of headwear such as caps, by the use of elastic or inelastic draw strings or adjustable bands, and also by the use of small inserts of elastic fabric in a leather sweat band. These types of adjustable headwear have been 10 objectionable by reason of cost, complexity, difficulty of manufacture, appearance and other reasons.

An object of the present invention is to provide a flexible article of headwear, such as a cap or beret which is self-adjusting and capable of fitting different sizes and shapes of head.

Another object is to provide such a flexible article of headwear which will remain firmly in place on the head without uncomfortable binding.

20 Another object is to provide a flexible, self-adjusting article of headwear which is of simple construction, good appearance and not expensive to manufacture.

Other objects will appear from the detailed description and drawing in which latter:

25 Fig. 1 is a vertical section through a lined cap showing one form of the invention;

Fig. 2 is a vertical section through an unlined form of cap showing a slightly modified construction;

30 Fig. 3 is a bottom view of the cap shown in Fig. 2;

Fig. 4 is a vertical section through a beret and showing another slight modification of the invention; and

35 Fig. 5 is a bottom view of the beret of Fig. 4.

Referring to the drawing, in Fig. 1 there is shown a cap having a body 1, the lower edge of which is inwardly and upwardly turned for a 40 short distance as shown at 2. Disposed between this upwardly turned portion 2 and the body 1 of the cap is a narrow relatively thick tape or band 3 of elastic fabric having a relatively strong contractive force, this band or tape being secured to the inwardly and upwardly turned portion 2 in any suitable manner as by the stitching 4. Disposed on the inner side of the upwardly turned portion 2 is an elastic sweat band 5, which is attached adjacent its lower edge to the lower part 45 of the upturned portion 2 as by the stitching 6. This sweat band may be made of any suitable narrow elastic fabric, such as a grosgrain ribbon, and it has a contractive force much less than that of the narrow band 3, for reasons which will be 50 hereinafter explained. Attached adjacent the

upper edge of the sweat band 5 is a lining 7 which is secured thereto by the stitching 8.

In the form shown in Fig. 2, the invention is applied to an unlined cap, the body 9 of which has its lower end inwardly and upwardly turned as shown at 10, and disposed between this upturned portion 10 and the body 9 is a narrow relatively thick elastic band or tape 11 having a relatively strong contractive force, while disposed on the inner side of the upturned portion 10 is an elastic sweat band 12, which may be grosgrain ribbon or other suitable elastic fabric. The narrow band 11, the upturned portion 10, and the sweat band 12 may be secured together by the lines of stitching 13. While the elastic sweat band preferably 15 extends entirely around the inner circumference of the headwear articles of the invention, in the case of a visored cap it is not essential that the elastic sweat band extend around the portion of the head opening adjacent the visor, and as shown 20 in Fig. 3 the portion 14 of the sweat band adjacent the visor 15 may be composed of leather, the balance of the sweat band being made of an elastic fabric band as above described. The cap shown in Fig. 1 may also have a visor and adjacent 25 leather sweat band portion such as shown in Fig. 3.

In Fig. 4 the invention is shown as applied to a beret, the body 16 of the beret being inwardly and upwardly turned at its bottom portion as shown 30 at 17, and secured to the inner side of this upturned portion is a narrow relatively thick elastic tape or band 18 having a relatively strong contractive force. This band may be secured in any suitable manner as by the stitching 19. An elastic 35 sweat band 20 of grosgrain ribbon or other suitable fabric is secured adjacent its lower edge to the lower part of the upturned portion 17 as by the stitching 21.

It has been found that if the sweat band be made 40 of an elastic fabric band having a relatively strong contractive force, it is stiffened to too great an extent and the strong elastic yarns required to be used are so large as to coarsen the fabric and make its appearance undesirable. 45 Moreover, if the sweat band itself have such a strong contractive force, it is liable to bind and be uncomfortable to the wearer. Therefore, by the present invention the sweat band is made of a material such as a grosgrain ribbon which 50 has a good appearance and is otherwise entirely suitable for use as a sweatband, and in the manufacture of this ribbon fine elastic yarns are incorporated so as to extend circumferentially of the article when the ribbon is in position in the 55

hat, the yarns exerting a relatively light gripping force. In order to give the desired contractive force so as to firmly hold the article on the head, the narrow elastic band or tape 3, 11 or 18 is provided, in which latter the elastic yarns used have sufficient contractive force to provide the desired grip. In addition, by reason of its thickness and position in the article, the narrow band gives a cushioning effect.

10 While not essential, it is preferred in making both the tape and sweat band to use an elastic yarn such as disclosed in patent to Adamson, No. 1,822,847, and having a core of rubber deposited directly from latex. Such rubber is of particular 15 value for the purposes of the present invention because of its superior resistance to the action of perspiration and/or organic cleaning fluids. In order to obtain the desired thickness and greater contractive force, the core of the elastic yarn used 20 in making the tape 3, 11 or 18 may be larger than that used for making the sweat band.

In manufacture of the headwear, the narrow elastic band and the elastic sweat band are both attached while slightly extended so that in the 25 finished article of headwear the body material adjacent the fastening of the elastic bands is slightly contracted or fulled. By reason of this when the article is worn it will grip the head of the wearer sufficiently to be firmly retained in 30 windy weather and yet at the same time the contractive effect is not sufficient to be uncomfortable. The sweat band per se, which is directly in contact with the head of the wearer and is of material having a relatively light contractive force, will grip without any discomfort to the wearer. The narrow band 3, 11 or 18, which has a 35 greater contractive effect, is disposed on one side or the other of the inwardly and upwardly turned portion of the body material but always between 40 the sweat band and main body and circumferentially co-extensive with the sweat band, and therefore does not exert pressure directly upon the head of the wearer, which might be uncomfortable. Also, as before pointed out, the narrow 45 elastic band gives a cushioning effect. In spite

of care in shrinking the material, a difficulty in ordinary caps has been the tendency for a perfect fitting cap to shrink after wetting and become too small. Previously the only way this could be compensated for was to make the cap slightly oversize at the back, as for instance in the rear sections or panels. This difficulty is avoided by the present invention. Finally, by reason of the elastic sweat band and auxiliary narrow elastic band, the headwear article is adapted to fit a 10 number of sizes and shapes of heads, thereby 15 greatly cutting down the number of sizes required to be kept in stock by a dealer. The invention is of course applicable to headgear for both male and female.

While specific embodiments of the invention have been shown and described, it is obvious that modifications may be made therein, and it is not desired to limit the invention otherwise than as set forth in the appended claims.

Having thus described my invention, what I claim and desire to protect by Letters Patent is:

1. A cap having its bottom edge turned inwardly and upwardly towards the crown of the cap, an elastic fabric sweat band extending at 25 least partly around the cap and secured to said upwardly turned bottom edge, and a circumferentially co-extensive elastic tape secured to said upwardly turned bottom edge, said tape being free from the outer wall of the cap and positioned 30 between said elastic sweat band and said outer wall so that it may move relative to said wall.

2. A brimless flexible article of headwear having its bottom edge turned inwardly and upwardly towards the crown, an elastic fabric sweat band 35 extending at least partly around said article and secured to said upwardly turned bottom edge, and a circumferentially co-extensive elastic tape of greater contractive strength than said elastic sweat band, said tape being free from the outer 40 wall of the article of headwear and positioned between the said band and said outer wall and secured in place therebetween so that it may move relative to said outer wall.

SETH ADAMSON. 45
